PLYWOOD BOWL OR SIMILAR ARTICLE

Harold Ambellan, New York, N. Y.

Application March 20, 1952, Serial No. 18,984

Term of patent 14 years

(Cl. D44—10)

To all whom it may concern:

Be it known that I, Harold Ambellan, a citizen of the United States of America, residing in city of New York, county of New York, and State of New York, have invented a new, original, and ornamental Design for a Plywood Bowl or Similar Article, of which the following is a specification, reference being had to the accompanying drawing, forming part thereof.

Fig. 1 is a top plan view of a plywood bowl, showing my new design;

Fig. 2 is a bottom plan view; and

Fig. 3 is a top perspective view thereof.

The dominant feature of my design resides in the overlapping portions at the end sections of the bowl as shown.

I claim:

The ornamental design for a plywood bowl or similar article, substantially as shown and described.

HAROLD AMBELLAN.
